HYDRAULICALLY OPERATED RECLINING CHAIR

Thomas E. Thomas and Hollie H. Phillips, Nashville, Tenn., assignors of one-third to C. R. Quarles, Nashville, Tenn.

Application May 1, 1937, Serial No. 140,228

5 Claims. (Cl. 155—116)

This invention relates to reclining chairs such as may be used in railway cars, busses, airplanes, etc., and particularly to a chair which is operated by hydraulic means.

The general object of the invention is to provide a chair of a simple construction which is so designed that the user may cause the chair seat to recline at any desired angle within a predetermined range and hold it at this angle or raise the chair to an approximately horizontal position, and a further object in this connection is to provide hydraulically operated means for raising or lowering the chair to any desired elevation and simultaneously changing its inclination. A further object in this connection is to provide means whereby the hydraulic pressure is automatically relieved immediately that the chair moves beyond a predetermined point, and another object is to provide spring means pivotally connecting the forward end of the chair seat with a fixed support to thereby secure a cushioning action against jars or vibrations.

Other objects will appear in the course of the following description.

Our invention is illustrated in the accompanying drawings wherein:

Figure 1 is a side elevation of a chair constructed in accordance with our invention.

Figure 2 is a vertical sectional view through the base and plunger and showing the pump and connections from the pump to the base in elevation.

Figure 3 is a front elevation of the chair shown in Figure 1.

Figure 4 is a sectional view of the relief valve.

Referring to these drawings, 10 designates a base which is, generally speaking, cylindrical in form but flares outward and downward at its lower end, which lower end rests upon the floor of the vehicle. Above the lower closed end 11 of the base there is a transversely extending septum 12 or wall which is formed with a central aperture 13. Extending upward from the wall 12 concentric to the outer wall of the base 10 is the cylinder 14 into the lower end of which the aperture 13 opens. The upper end of the base is closed by a cap 15 having threaded engagement with the base and the center of this cap is formed with a plunger aperture and with a gland 16 or stuffing box. A plunger 17 operates through this gland as shown clearly in Figure 2. The plunger may be of any suitable construction and provided with any suitable rings for preventing passage of liquid around the plunger and out through the gland 16. The upper end of the plunger is formed

with a knuckle 18. Supported by the plunger is a chair seat 19 of a particular construction which will be hereafter stated, this chair seat having a back 20. Extending upward and outward from the front of the base 10 are a plurality of brackets 21, the brackets being joined at their lower ends, the middle bracket extending directly upward and outward while the lateral brackets extend upward, outward and laterally, as shown in Figure 3. These brackets at their upper ends are formed with beads 22 through which a pin 23 passes. The seat of the chair includes longitudinally extending elements 24 of metal, the forward ends of which extend beyond the forward edge of the seat and extend outwardly, downwardly and inwardly, as at 25, (see Figure 1) and are then formed with eyes 26 through which the pin 23 passes. It will be seen that thus a hinge joint is provided between the brackets 21 and these extensions 25 of the chair seat. These extensions 25 are resiliently flexible. The center of the chair seat is provided with a downwardly extending clevis 26 which embraces the reduced portion 18 and is pivoted thereto by a pivot pin 27. It will thus be seen that as the plunger 17 rises, the chair will rise so that the seat will be carried up into an approximately horizontal position while when the plunger is lowered, the chair will be lowered from the full line position in Figure 1 to or toward the dotted line position in Figure 1, this action being permitted by the hinge joint 23.

Mounted upon the plate 11 or in any other manner associated with the base 10 is a pump cylinder 28 having the usual plunger or piston 29 therein, this piston being connected by a shackle 30 to a transversely extending lever 31 pivotally mounted on a bracket 32 attached to the base, this bracket being disposed relatively close to the pump cylinder so that the lever 31 is formed with a short arm and a long arm. The long arm extends transversely across beneath the chair and is connected by a link 33 to a bell crank lever 34 pivoted upon a transversely extending pivot rod 35 which may be welded, bolted or otherwise attached to the brackets 21. One arm of this bell crank lever is upwardly extended to form a long handle 36 extending up beyond the adjacent arm 31 of the chair.

As shown in Figure 2, the space between the outer wall 10 of the base and the cylinder 14 constitutes a reservoir designated 37. This chamber 37 is connected by a pipe 38 to the lower end of the pump cylinder 28 and disposed within the length of this pipe or duct 38 is a check valve 39.

shown diagrammatically in Figure 2 and designated 39. Thus on an upward movement of the piston 29 liquid will be drawn from the reservoir 37 into the pump barrel or cylinder 28. Upon a downward movement of the piston 29, however, the check valve 39 will close, preventing the discharge of liquid back into the reservoir. Leading from the lower end of the pump barrel or cylinder 28 is a pipe 40 which leads into a T 41, this having an upwardly extending branch discharging into the space below the partition or wall 12 and thus discharging through the aperture 13 into the space below the plunger 17. A check valve shown diagrammatically in Figure 2 and designated 42 is disposed in the length of this pipe 40 and acts, of course, to permit the discharge of liquid from the pump into the base below the plunger but prevents the return of this liquid upon an upward movement of the pump plunger or piston.

Leading from the third branch of the T 41 is a pipe 43 which is connected to a valve casing 44 which in turn has a pipe connection 45 with the interior of the reservoir 37. The valve 46 disposed in this valve casing is mounted upon a spindle 47 carrying an outwardly extending arm 48. This arm is connected by a link 49 to a lever 50 pivoted upon a transverse pivot rod 51 which may also be spot-welded, pinned or otherwise rigidly connected to the brackets 21. This lever 50 has an upwardly and rearwardly extending arm 52 which terminates at its upper end in a knob 53 which is disposed above the chair arm 36, as shown in Figure 1. The upper end of this arm 52 is disposed immediately in front of a laterally projecting member 54 shown as formed upon or as part of the arm 36 of the chair. A spring 55 urges the arm 48 to a horizontal position and in this position of the parts, the valve 46 is closed and does not afford communication between the interior of the reservoir 37 and the relief pipe 43. When, however, the handle 52 of lever 50 is shifted upward and forward, it causes the relief valve 46 to turn to a position connecting the interior of the reservoir with relief pipe 45. This permits the plunger 17 to descend and forces all the liquid beneath the plunger out through the T 41 into the pipe 43 and thus back into the reservoir.

It will thus be seen that the reservoir is self-contained within the base and the chair requires no connections to any other reservoir or tank. The body of the chair may, of course, be of any suitable material or any particular construction desired but, as illustrated, the body of the chair consists of an exterior U-shaped frame 56 having cross-bars 57 to which the upper ends of the metallic strips 24 are attached, the frame 56 being angularly extended or horizontally extended so as to form the frame for the seat of the chair and being connected by a transverse cross-bar 58 over which the strips 24 extend and to which the arm rests 36 are connected, as shown in Figure 3. The strips 24 are resilient so as to provide a cushioning action and obviously the chair might be upholstered if desired, or have any other desired structure.

The operation of this structure will be obvious from what has gone before. When it is desired that the chair seat shall be horizontal, the sitter operates the pump handle 35, causing liquid to be forced in beneath the plunger 17 and this raises the chair seat, the forward end of the seat pivoting upon the transverse rod 23. When the plunger 17 has risen as far as it should, the element 54

which forms part of the arm rest 36 will engage the knob 53 and this will act to open the relief valve so that no further upward movement of the chair can be secured. As soon as the relief valve is opened, the chair will commence to descend but as soon as it descends a very slight distance, the spring 55 will shift the relief valve to a closed position, thus holding the liquid beneath the plunger and the chair in raised position. If the occupant desires to lower the chair to or toward the dotted line position in Figure 1, the occupant lifts up on the handle 53 which opens the relief valve and the plunger 17 then moves downward until the occupant of the chair moves the knob 53 back to its normal position, which closes the relief valve and again the plunger will be held in its adjusted position. With this mechanism, it is obvious that the chair may be raised to a horizontal position or lowered to a fully inclined position or to an intermediate position at the will of the operator. It is also obvious that the curved springs or resilient portions 25 of the metallic strips 24 not only constitute pivotal supports for the forward end of the chair and constitute springs partially supporting the chair but as these spring portions 25 extend outward, downward and inward in a curve, they form rounded surfaces beneath the knees of an occupant.

While we have illustrated one particular form of chair and certain specific arrangement of parts yet, of course, it will be understood that different types of chairs might be used and that the arrangement shown might be varied without departing from the spirit of the invention as defined in the appended claims.

This chair is particularly adapted as a reclining chair for busses, trains, airplanes or in other places where sitting is required for long periods of time.

What is claimed is:—

1. In a reclinable chair having a seat, the combination of a base, means on the base pivotally supporting the front of the seat, hydraulic means for raising the seat to a horizontal position, manually operable means for operating the hydraulic means and including an operating lever extending upward beside the seat and closely adjacent thereto, a relief valve for relieving pressure in the hydraulic means to permit the descent of the seat to a rearwardly and downwardly inclined position, means yieldingly urging the relief valve to a closed position, a manually operable lever operatively connected to the relief valve and constructed and arranged to shift the relief valve to an open position against the action of said urging means, and coacting means on the chair and lever constructed and arranged to cause an automatic operation of the lever and the relief valve when the rear end of the chair has lifted beyond a predetermined point and until the chair has descended slightly.

2. A reclinable chair comprising a base, a bracket extending upward and forward from the base, a chair seat operatively pivoted to the bracket at its forward end, hydraulic means for supporting the seat in a horizontal position, including an hydraulically operated plunger pivotally connected to the seat, a relief valve yieldingly urged to a position normally preventing reverse movement of the liquid beneath the plunger, a manually operable pump, means disposed closely adjacent the chair seat for operating the pump to thereby raise the plunger to place the seat in a horizontal position, a manually operable

lever disposed closely adjacent the seat and operative to open the relief valve, and means for automatically operating said lever to open the relief valve when the rear end of the chair has 5 risen to a predetermined point and until the chair has descended slightly.

3. A reclinable chair, including a hollow base formed to provide a central cylinder and a surrounding reservoir, a vertically movable plunger 10 operating in the cylinder, a bracket extending upward and forward from the base, a chair having a seat and a back, the middle of the seat being operatively pivoted to and supported by the plunger, the forward end of the seat being 15 operatively pivoted to said bracket, a pump carried by the base at one side thereof, the pump having an inlet pipe leading from the reservoir and an outlet pipe having a branch leading into the plunger cylinder, a relief pipe extending into 20 the reservoir and connected to the outlet pipe of the pump, a relief valve in the relief pipe yieldingly urged to a closed position, a transversely extending lever operatively pivoted intermediate its ends to the base and at one end operatively 25 connected to the pump, a bell crank lever having a short arm connected to the long arm of the transverse lever and having its long arm extending upward in close proximity to the seat, a second manually operable lever operatively connected 30 to the relief valve and having an arm extending up beside the chair of the seat, the chair and

lever having coating means constructed and arranged to shift the lever to a position to open the relief valve when the rear end of the chair has been lifted to a predetermined point and hold the relief valve open until the chair has slightly 5 descended.

4. In an hydraulically operated reclinable chair, a valve which when opened permits the descent of the rear end of the chair, means urging the relief valve to a closed position, and manually controllable means connected to the relief valve whereby the relief valve may be manually opened, said means extending into the path of movement of a part of the chair and being constructed and arranged to be engaged by the chair 10 when it is in an approximately horizontal position to thereby open the relief valve and permit the chair to descend slightly.

5. A reclinable chair, including a base, a bracket extending upward and forward from the base, 20 a chair seat having outwardly and downwardly curved resilient members at its forward end pivotally connected to said bracket, and manually controllable means whereby the chair seat may be raised from a downwardly and rearwardly inclined position to a horizontal position or lowered to a downwardly and rearwardly inclined position. 25
